UNITED STATES PATENT OFFICE.

ALFRED H. ARMOR, OF CHICAGO, ILLINOIS.

AIR-PUMP.

SPECIFICATION forming part of Letters Patent No. 258,347, dated May 23, 1882.

Application filed June 30, 1881. (No model.)

To all whom it may concern:

Be it known that I, ALFRED H. ARMOR, a citizen of the United States, residing at Chicago, in the county of Cook and State of Illinois, 5 have invented certain new and useful Improvements in Air-Pumps, of which the following is a specification.

My invention relates to improvements in air-pumps; and it consists in the construction and 10 arrangement of parts, as hereinafter more fully described and claimed.

In the annexed drawings, Figure 1 is a sectional elevation of my improved air-pump. Fig. 2 is an enlarged section of the same, showing details of construction. Fig. 3 is a top view of the pump. Fig. 4 is a top view of the lower piston-plates. Fig. 5 is a cross-section of the plates, and Fig. 6 is a plan view of the upper piston-plate and hub.

20 Similar letters refer to similar parts throughout the several views.

A is a cast-iron cylinder, having a detachable bottom, B, the outside of which is convex and the inside concave to correspond with the 25 plate of the plunger. At the top of the cylinder is a ring, C, having a screw-thread, by means of which it is detachably secured thereto. This ring is provided with arms D, which incline inwardly and upwardly and connect 30 with a smaller screw-threaded ring, E, surrounding the piston-rod, as shown in Figs. 1, 2, and 3.

F is the cover of the cylinder, and is provided with a circular opening, having an inwardly-beveled edge for the reception of a 35 smaller detachable cover, G, the edge of which is beveled to correspond with the outer annular cover. In the center of the cover G is an opening of sufficient size to allow the piston-rod to work freely, and this cover is capable of being readily lifted, so as to allow the piston 40 to be oiled without the usual necessity of withdrawing it from the cylinder. A packing-ring, α , is placed between the cover F and upper end 45 of the cylinder.

H is a tubular piston-rod, provided with a handle, I, and having on its outer side a screw-thread, b . This tubular piston-rod incloses a 50 rod, c , which is held in place by means of a nut or collar, d , which is supported by a screw-nut, e , on the lower end of the tubular rod H.

The rod c is smaller in diameter than the inside diameter of the tubular rod H, and extends upward therein for about half-way above the lower end of the latter. At the top of the 55 rod c is a nut, f , which is nearly of the same diameter as the interior of the tubular rod H, for the purpose of keeping the rod and piston steady by preventing the rod c from moving laterally within the tube H. Near the lower 60 end of the rod c , at the point where it enters the hubs of the piston-plates, is a nut, g , for the purpose of tightening the piston-plates together. The lower end of the rod c is screw-threaded for attachment of the piston-plates. 65

The piston K is composed of the detachable plates h i . These plates are provided on their upper faces with radial strengthening-ribs h and concentric hubs m n , the hub m of the upper plate, h , being of sufficient size to receive the hub n of the lower plate, i , as shown in Figs. 2 and 5. The inner or adjacent surfaces of the piston-plates h i are provided near their edges with rings or circular flanges o o , which are beveled, as shown, so that the ring on the lower plate will fit readily within the ring on the upper plate. On the outer sides of these rings are ledges, between which is placed the leather packing p , a rubber packing-ring, s , being arranged to surround the 80 same, and the whole is securely held in place by tightening the nut g on the rod c , which forces the piston-plates together, a thin flat ring, t , being preferably arranged, as shown in Fig. 5, for the packing to rest against. Owing 85 to the arrangement of the piston-plates and their hubs, the hub n on the lower plate can be made sufficiently long to have a screw-thread on its inside of such length as to afford a long hold for the screw-threaded end of the 90 rod c . This is an important advantage, as a short screw-thread would not give a sufficient hold and would be liable to pull off.

L in Fig. 3 represents a vent consisting of a screw-threaded tube having a screw-cap, and 95 is arranged near the bottom of the cylinder for the purpose of permitting the entrance and escape of air.

M are nipples for the attachment of tubes, by means of which the pump is connected with 100 vessels containing the liquids to be acted upon. w w are lugs on the bottom of the cylinder,

by means of which it may be screwed or otherwise fastened to a table or platform.

When the piston-plates are resting on the bottom of the cylinder, if the handle I is turned 5 the piston will be drawn up to the top of the cylinder, carrying the plates and creating a vacuum in the cylinder between the same, provided the vent L and nipples M are closed. If the nipples M are connected with closed vessels 10 containing milk or other liquids to be acted upon, such contents will be purified by the passage of air and odors from said vessels into the interior of the cylinder. On cutting off the communication between the cylinder and vessels and opening the vent L the air in the cylinder will be expelled therefrom upon the descent of the piston without being returned to the vessels. By connecting the pump with two 15 vessels the contents of each may, if desired, be alternately compressed and exhausted.

In order to tighten or loosen the piston-plates *hi*, the piston is drawn to the top of the cylinder.

der, so that the hub *m* will come up through the opening in the cover, when, by simply turning the nut *g* by means of a wrench, the 25 piston plates will be forced together or separated, as desired.

Having thus described my invention, what I claim as new, and desire to secure by Letters Patent, is—

1. The combination, with the piston K and tubular piston-rod H, having screw-thread *b* and nut *e*, of the rod *c*, provided with nuts *d* *g* *f*, substantially as shown and described. 30

2. The combination, with the ribbed and flanged plates *h i*, having concentric hubs *m n*, of the tubular screw-threaded piston-rod H, nut *e*, and rod *c*, having nuts *d g f*, substantially as shown and described. 35

ALFRED H. ARMOR.
